UNITED STATES PATENT OFFICE.

JAMES A. DOBBS AND RICHARD KREBS, JR., OF OLIVE, CALIFORNIA.

METALLIC RAILWAY-TIE AND RAIL-FASTENER.

1,106,636.

Specification of Letters Patent. Patented Aug. 11, 1914.

Application filed February 3, 1914. Serial No. 816,149.

To all whom it may concern:

Be it known that we, JAMES A. DOBBS and RICHARD KREBS, Jr., both residing at Olive, in the county of Orange and State of California, have invented certain new and useful Improvements in Metallic Railway-Ties and Rail-Fasteners; and we do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in railway equipment and particularly to the rail ties and fasteners therefor, the object of the invention being to produce a metallic tie provided with a positive fastener whereby the rails may be set in the position desired and at the same time fastened as securely therein as those spiked to wooden ties.

Further, we aim to produce a tie, which by reason of its shape, will give the greatest bearing on the rail at the outer ends of the tie where it is most needed and at the same time prevent the track from becoming center-bound which is one great trouble now encountered in the construction of railways.

We also aim to shape the tie so as to keep the track in perfect alignment and provide the fastening in such a manner as to render it impossible for the track to spread or become loosened to such a degree as to render it dangerous.

As is a well known fact, the supply of wooden ties is becoming almost exhausted and the construction of railroads will require either concrete or metallic ties. Also the wooden ties deteriorate very rapidly, whereby by the use of metallic ties, the life of a railroad would be greatly extended and these advantages will also be gained by the use of our device in addition to those enumerated above.

A further object of the invention is to produce a simple and inexpensive device and yet one which will be exceedingly effective for the purposes for which it is designed.

These objects, we accomplish by means of such structure and relative arrangement of the parts as will fully appear by a perusal of the following specification and claim.

On the drawings, similar characters of

reference indicate corresponding parts in the several views.

Figure 1 is a top plan view of our improved tie and fastener showing the rails in position thereon. Fig. 2 is a side elevation of the same showing the rails in section. Fig. 3 is an enlarged top plan view of one end of the tie. Fig. 4 is a sectional view taken on a line X—X of Fig. 3. Fig. 5 is an enlarged view in section of one end of the tie showing the method of securing the rail to the tie. Fig. 6 is a top plan view of a fastening wedge. Fig. 7 is a side elevation of the same.

Referring now more particularly to the characters of reference on the drawings, the numeral 1 designates the tie proper which is hollow and substantially trough shaped. The tie is enlarged at each end and its sides slope inwardly to give it a lesser width at the center as shown clearly in Fig. 1. The tie is provided at each end with slotted plates 2, the sides of which plates slope diagonally with respect to the center lines of the rails 3 and each plate is provided on each side with an overhanging flange 4. Through the bottom of each of the plates 2 on which the rails rest is provided a pair of elongated slots 5 and 6 for the purpose of receiving securing bolts as will presently appear.

The numeral 7 designates wedges adapted to be driven upon the slotted plates 2 and under the flanges 4 on each side of the rail and from opposite sides of the tie, which wedges engage the sides of the rail and the sides of the slotted plates 2 to clamp the rail in fixed position. By reason of the wedges this fixed position may be accurately determined to center the rail properly and then a bolt 9 is projected through each of the slots 5 and through a bolt hole 8 in each wedge and similarly a bolt 10 is projected through each of the slots 6 and a slot 11 in each of the wedges, such bolts having, of course, suitable securing nuts. The elongated shape of the slots 5 and 6 of the bolts 11 permits these bolts to be set after the rail is properly wedged into shape, the elongation of such slots allowing for slight movement one way or the other and yet when once set the wedges are held in fixed position by reason of the position of the slots 6 and the circular holes 8. Beneath the nut on each of the bolts 10 and resting on the

flanges of the rail and on the wedges is a strong metal washer 12, which washers hold the rail and wedges in fixed position in the slotted plates 2.

5 From the foregoing description it will readily be seen that we have produced such a device as substantially fulfills the objects of the invention as set forth herein.

While this specification sets forth in detail the present and preferred construction of the device, still in practice, such deviations from such detail may be resorted to as do not form a departure from the spirit of the invention.

10 15 Having thus described our invention, what we claim as new and useful and desire to secure by Letters Patent, is:

A device of the character described comprising the combination of a metallic tie 20 provided with a horizontal slotted plate at each end, a rail disposed on each plate, the sides of said plates being disposed obliquely with respect to the center lines of said rails, an overhanging flange on each side of each

plate, a pair of elongated slots in the bottom 25 of each plate on each side of each rail, a wedge projecting into each slotted plate on each side of said rail and from opposite sides of said tie, each wedge being provided with an elongated slot and a round orifice adapted to coincide with one pair of said slots in said plates, a bolt projecting through each of said slots and the corresponding slot and orifice in each wedge and provided with nuts, a washer disposed between the nut of 30 one of said bolts on each side of each rail and engaging the flange of said rail and said wedge, as described.

In testimony whereof we affix our signatures in presence of witnesses.

JAMES A. DOBBS.

RICHARD KREBS, JR.
